Attorneys.

UNITED STATES PATENT OFFICE

ARTHUR ERNEST JERRAM, LEICESTER, ENGLAND

STARTING DEVICE FOR MOTOR-DRIVEN MACHINES

Application filed November 21, 1927, Serial No. 234,863, and in Great Britain December 22, 1926.

This invention relates to motor-driven machines of the kind that are steered by a driver who is usually not carried by the machine but walks with it or sits on a part, such as a trailer, driven by the machine. The invention is particularly applicable to motor-driven lawn-mowers and like light machines having a motor in the form of an internal-combustion engine.

10 This invention has for its main object to render the starting of the motor of such movable machines more easy as compared with the usual method of cranking round an engine-driven shaft by means of a handle on the latter.

According to an important feature of the invention, there is provided in a motor-driven movable machine of the kind described, the combination with a relatively low-lying shaft 20 arranged to be rotated by a pull on an independent flexible tie having one end wound thereon, or on a part operatively connected therewith, and thereby start the motor, of a part that is arranged to constitute a support 25 for a foot of the operator for steadyng the machine whilst the operator is pulling the tie, and is so placed as to enable the operator to use his muscular strength to advantage. This arrangement obviates the necessity for 30 the driver to stoop down to a shaft near the ground and crank it round by hand whilst in an awkward position for such an operation, and enables him to remain erect and readily start the motor whilst in such position.

35 According to another feature of the invention, the said part receiving the flexible tie, for example a strap, is in the form of a pulley, having in its periphery a tie-receiving slot that lies at an acute angle to the adjacent peripheral surface, and extends inwardly and forwardly in the direction of rotation of the pulley. This construction ensures that the tie when unwound from the part to which it is applied shall at once leave the same and not be wound thereon in the reverse sense when the motor is running under its own power.

40 In order that the invention may be clearly understood it will now be described by way of example only, with reference to the accompanying drawing as applied to a motor-

driven lawn-mower, although it is to be understood that the invention is not restricted thereto, as it is also applicable to other machines of the kind set forth above. In said drawing:

55 Figure 1 is a perspective view of part of the mower showing the improved starting device comprising a pulley and tread-plate applied thereto;

60 Figures 2 and 3 show the pulley in side elevation, partly in section, and in end elevation, respectively, and

65 Figures 4 and 5 show the tread-plate in front elevation, and transverse sectional elevation, respectively.

65 Like reference characters designate like parts in all the views.

Referring to the drawing, the power-driven lawn-mower has an internal-combustion engine 10 which can be started by rotating a 70 shaft 11 that extends at one end through one side of the frame of the machine where it carries a pulley 12 just outside the frame near the end thereof carrying the handles 13. In the construction illustrated, the shaft 11 is 75 coupled by an automatically adjustable coupling with the engine crankshaft and lies relatively low down near the ground.

As shown in Figures 2 and 3, this pulley has an internally screwthreaded boss by 80 which it can be screwed on the shaft 11, and two flanges 14, 15. The flange 14 is larger and situated towards the threaded end of the pulley, whilst the flange 15 is smaller and situated towards the other end 16 which is 85 recessed to provide a chamber 17 extending inwards nearly as far as the flange 14, in which chamber a lock-nut 18 for locking the pulley on its shaft can be housed. The body of the pulley between its flanges has formed 90 in its periphery a slot 19 that lies at an acute angle to the adjacent peripheral surface, and extends inwardly and forwardly in the direction of rotation of the pulley for receiving one end of a flexible tie 20, such as 95 a leather strap, which is then wrapped about the pulley between its flanges with several superposed turns, coil over coil, in the direction in which the shaft is to be rotated on starting the engine. The strap thus has its 100

temporarily held end folded back on the end part thereof in the slot, so that when unwinding the strap its held end will readily leave the slot as there is no knot or like stop for holding it therein. The flanges 14, 15 prevent loose material from being caught in the slot when the motor is working and thereby ensure safety whilst the machine is in use. The end 16 of the pulley is preferably conical outside for preventing loose material from being wound up on it, and has an internal annular groove 21.

A tread-plate 22 constituting a support for the foot of the operator is provided for 15 steadyng the machine while the operator is pulling the strap 20. As shown in Figures 4 and 5, this tread-plate which may be a casting, has a curved foot-supporting surface formed by stud-like projections 23 to provide a roughened surface having at the centre a recess 24 formed in a boss 25 at the back of the plate. This boss is perforated to receive a bolt by which the plate can be firmly fixed 20 on the machine, with the head or one or more nuts of the bolt accommodated in the recess 25 24 out of reach of a foot placed on the plate.

Such a tread-plate, which is distinct from the frame of the machine, may be fixed on 30 the mower substantially in front of the pulley 12, so that when the operator takes a firm hold of the free end of the strap and places on the plate one foot, say the left foot, he can thereby secure the machine from movement and obtain a purchase on the strap, so 35 that he can exert great muscular effort and spin the motor at a speed, hitherto unobtainable, by merely cranking the engine-shaft round by hand. In this way, starting of the 40 motor is greatly facilitated, particularly in the case of two-stroke engines and all danger of damage to the operator through a backfire is obviated. As illustrated in Figure 1, the 45 tread-plate is bolted to a boss formed on a detachable cover-plate 26 of a gear-box containing change-speed gear arranged between the shaft 11 and the driving roller 27 of the mower, but it may be mounted at some other convenient situation if desired.

Various modifications may be made in the 50 details of construction described above without departing from the invention as defined in the claims. In some cases, the tie-receiving slot may be open-ended at one or both 55 ends of the pulley, in which construction one or both of the flanges aforesaid, if provided, will also be slotted, but this modification is not preferred. Also, some relatively low-lying shaft other than that described may be 60 rotated by the unwinding of the tie and arranged to start the motor.

I claim:

1. A motor-driven movable machine of the kind described comprising in combination, 65 a low-lying shaft adapted, upon rotation,

start the motor of the machine, a flexible tie having one end wound on a part operatively connected with said shaft and adapted to be pulled to rotate the shaft, and a relatively fixed support for a foot of the operator so 70 secured to the machine as to steady the latter whilst the operator is pulling the tie, and as to enable the operator to use his muscular strength to advantage.

2. A motor-driven movable machine of the kind described comprising in combination, a low-lying shaft adapted, upon rotation, to start the motor of the machine, a flexible tie having one end wound on a part operatively connected with said shaft and adapted to be 80 pulled to rotate the shaft, and a roughened tread-plate secured to a relatively fixed part of the machine at a position close to the line of pull of the said tie on the shaft so that the operator may rest his foot thereon when 85 pulling the said tie.

3. A motor-driven movable machine of the kind described comprising in combination, a low-lying shaft adapted, upon rotation, to start the motor of the machine, a flexible tie having one end wound on a part operatively connected with said shaft and adapted to be pulled to rotate the shaft, and a tread-plate detachably secured to a relatively fixed part of the machine frame and facing the operator so that he may rest his foot thereon when 95 pulling the said tie.

4. A motor-driven movable machine of the kind described comprising in combination, a low-lying shaft adapted, upon rotation, to 100 start the motor of the machine, a slotted pulley fast on said shaft, a flexible tie having one end portion inserted in the slot and wound around said pulley, which said slot in the pulley extends inwardly from the exterior 105 thereof in a forward direction at an acute angle to the adjacent peripheral surface of the pulley, and a tread-plate for a foot of the operator so secured to the machine as to steady the latter whilst the operator is 110 pulling the tie.

5. A motor-driven movable machine of the kind described comprising in combination, a low-lying shaft adapted, upon rotation, to start the motor of the machine, a slotted pulley fast on said shaft, flanges on said pulley extending around the periphery thereof and spaced apart from each other, the said slot in the pulley lying between the flanges 115 and having its ends closed thereby, which said slot also extends inwardly from the exterior of the pulley in a forward direction, a flexible tie having one end portion inserted in the slot and wound around the pulley, and a tread-plate for a foot of the operator so 120 secured to the machine as to steady the latter whilst the operator is pulling the tie, and as to enable the operator to use his muscular strength to advantage.

6. In a motor-driven movable machine of 130

the kind described, the combination of a low-lying shaft adapted, upon rotation, to start the motor of the machine, a starting device comprising a flexible tie that has one end wound on a part operatively connected with said shaft, and is adapted to be pulled to rotate the shaft, and a tread-plate that is mounted on the machine relatively low down near the ground, and in such positional relationship to the said part around which the tie is wound, as to enable the foot of the operator conveniently to provide the requisite reaction to the pull on the tie when starting the motor, and to enable the operator to use his muscular strength to advantage.

In testimony whereof I affix my signature.

ARTHUR ERNEST JERRAM.
